UNITED STATES PATENT OFFICE

ALFRED RUTTIMAN, OF GARDNER, MASSACHUSETTS, ASSIGNOR TO FLORENCE STOVE COMPANY, OF GARDNER, MASSACHUSETTS, A CORPORATION OF MASSACHUSETTS

IGNITION DEVICE

Application filed June 3, 1926. Serial No. 113,497.

This invention relates to ignition devices, having particular reference to such a system as may be used with oil burning stoves to ignite the same.

5 The principal object of the invention is the provision of a sparking plug which will operate under the so-called high tension or jump spark system, which when operated will heat small quantities of oil to a temperature favorable for ignition by the spark from said device.

10 Another important object is the provision of a spark plug which by reason of the use of a certain type of electrode, will more readily burn off any accumulated carbon deposited thereon thus insuring positive sparking and consequent ignition.

15 To this end my invention consists in a unipolar spark plug having a terminal composed of a plurality of fine, heat resisting, impeded heat conductive, current conducting wires. Such wires may be composed of nichrome material or other heat resisting metal or alloy and may be enclosed in an enamel sheath, the 20 ends of the wires being exposed. The spark gap is formed between such electrode or terminal and a part of the metal burner bowl of the oil stove to which the device is attached, the spark being allowed to jump in proximity 25 to the stove kindler saturated with fuel oil.

30 The invention further consists in the novel arrangement, construction and combination of parts hereafter described and shown in the accompanying drawings in which:

35 Fig. 1 is a side elevation of one form of device located in the burner bowl of an oil stove.

Fig. 2 is a plan view of the device of Fig. 1.

Fig. 3 is a view of a modified form.

Fig. 4 is a view of another form.

40 Fig. 5 is a view of still another form.

Fig. 6 is an elevation of the device of Fig. 1 along the line 6-6.

In the drawing I have illustrated in Fig. 1 a burner oil bowl generally at 1 which is of the ordinary type as used in a constant oil

level, oil burning stove. This bowl is adapted to receive oil from a supply pipe 2 secured thereto. Fixture 3 may be attached to any desired form of burner raising or lowering means, (not shown) so that by raising or lowering the bowl above or below the maintained oil level, the burner may be extinguished or ignited, all as is well known.

50 A kindler 4 of asbestos or other suitable material is located in the bowl 1 and becomes saturated with oil flowing from the supply pipe 2. The oil in the kindler 4 in this type of stove is burned directly therefrom and heats a chimney (not shown) which rests upon the bowl 1.

55 Secured in an angular manner through the wall of the bowl 1, I provide a cylindrical sleeve 5, the upper portion of which terminates close to the upper portion of the kindler 4.

60 Within the metal sleeve 5 is a spark plug 6 of porcelain or the like (Fig. 1) having an axial aperture 7 therein occupied by a wire 8 one end of which is connected to a jump spark coil shown diagrammatically at A, supplied 65 with current from dry cells 10, the other end of which grasps one or a plurality of fine wires 9 of a heat-resisting nature of heat impeded conductivity. These wires may be of nichrome or similar material, partially enclosed by the plug 6, or an enamel sheath as hereinafter described. The size of these wires are to be such that the passage of a suitable amount of current therethrough will 70 render them red hot even though coated with carbon or fuel oil.

75 A push button 11 may be used to permit the coil to be energized to cause a spark to jump from wires 9 to bowl 1, or sleeve 5.

80 Any carbon deposited on the wires 9 will be instantly burned off when the switch 11 is thrown, so that there will be no failure to spark on this account. Likewise any fuel oil on the wires 9 will be instantly vaporized 85 90

so that the spark may ignite the same without difficulty.

If the wires 9 are of sufficient length, the spark may occur between them and the upper ledge of the burner bowl proper. At all events this sparking occurs in a zone where fuel oil vapors exist, and the ignition is expedited by oil vaporized from the heated electrode itself.

10 In Fig. 1 the electrode end of the insulator is tapered as at 12 to obtain uniform strength, to increase the surface resistance and get an air space between plug section 12 and tube 5 as large as possible. At the neck of tapered portion 12, the enlarged plate like rib section 13 adds further resistance to leaking paths of the high voltage current, hinders dirt from falling into tube 5, and provides a radiating periphery for the discharge direct 20 through the air into upper edge of tube 5.

When the free spark, due to a dirty or carbon covered plug, takes a short circuit through the carbon on the plug instead of jumping freely to the burner bowl, the ignition will take place anyway by reason of the heat from the incandescent electrode made up of the bundle of tiny wires of heat impeded conductivity, the oil on the kindler being vaporized by the heat of the electrode 30 and ignited by the incandescent character of the electrode.

The electrode 14 of Fig. 3 is shown to be of more nearly cylindrical form and with a rounded head.

35 In Fig. 4 I have shown the insulator as provided with a head 15 having a series of spaced apart concentric grooves which I have found to be an advantageous form of device.

While the material of which the insulator 40 may be made includes porcelain, yet in some instances I have found that a cheaper material may be used such as lava or some other insulating substance. It has been found desirable to provide the insulator with an enameled cap 16 having a tip 17 through which the wires 9 may project and act as before. Such a structure prevents to a maximum extent the sticking or accumulation of carbon 45 on that part of the device surrounding the electrodes 9 without making necessary constructing the entire insulator from an expensive material such as porcelain. It has been found that where the wires 9 are enclosed in an enamel sheath, only relatively 50 small surfaces of such wires are exposed to moisture and carbon. Such tiny spots are quickly dried and the carbon burned off locally so that the essential high plug resistance is restored by the heating effect of the jump 55 spark current and the spark discharge.

In the embodiment of Fig. 5, the insulator and its containing sleeve rise directly within the oil bowl 1, and between the ends of the wick or kindler.

60 The end of the plug consisting of tiny heat

resisting wires of heat impeded conductivity is unipolar in that it is the only pole which serves as an ignition means. The plug is unipolar in the sense that the high igniting temperature of the spark always occurs on the plug and not on the bushing holding the plug. This is so whether the current surges are stronger or directed in the one or the other direction.

I claim:

1. In combination an annular oil bowl having a kindler therein, jump spark electrodes one of which is made up of a group of tiny heat resisting unipolar electrode wires of heat impeded conductivity and together with the other jump spark electrode, providing a gap in proximity to said kindler, whereby on the one hand the spark will ignite the oil with which said kindler is saturated or in the event of a short circuited spark gap said oil will be vaporized and ignited by the incandescence of said tiny wires, substantially as described.

2. In combination, an oil burning stove having an annular burner bowl, a kindler in said bowl, a sleeve extending through the inner wall of said annular bowl to a point above the oil level in the bowl, a unitary unipolar spark plug in said sleeve, said spark plug comprising an insulating sheath extending above the oil level in the bowl, an electrode within said sheath, the upper end of said electrode forming a preheater structure comprising a plurality of tiny heat resisting, current conducting, unipolar electrode wires of heat impeded conductivity in cross-section, said tiny wires extending slightly beyond the end of the sheath and into proximity to and directly above said oil and kindler and upon being rendered incandescent by passage of current therethrough, adapted to burn off oil or carbon thereon and to preheat and vaporize the fuel oil.

3. In combination, an oil burning stove having an annular burner bowl, a kindler in the bowl, a sleeve disposed at an angle and projecting upwardly and outwardly in a radial plane through the inner wall of said annular bowl to a point above the oil level in the bowl, a unitary unipolar spark plug frictionally received within said sleeve, said spark plug comprising an enamel sheath extending beyond said sleeve and above said oil level in the bowl, an electrode within said enamel sheath, the upper end of said electrode forming a preheater structure comprising a plurality of tiny heat resisting, current conducting, electrode wires of heat impeded conductivity in cross-section, said tiny wires being disposed to extend slightly beyond the end of the enamel sheath and into proximity to and directly above said oil and kindler and upon being rendered incandescent by passage of electricity therethrough, to burn off any oil or carbon thereon and to preheat and vaporize

the fuel oil to be ignited by a spark caused by a jump spark coil in series with a source of power, said spark jumping from said tiny wires to said sleeve or burner bowl in proximity to the kindler saturated with fuel oil, and in case of short-circuited spark gap, said tiny wires being constructed and disposed to ignite the vaporized fuel by their incandescence alone.

10 In testimony whereof, I have affixed my signature.

ALFRED RUTTIMAN.
